US0D1021875S

(12) **United States Design Patent** (10) **Patent No.:** **US D1,021,875 S**
(45) **Date of Patent:** **** Apr. 9, 2024**

(54) **MICROPHONE**

(71) Applicant: **Freedman Electronics Pty Limited**,
Silverwater (AU)

(72) Inventors: **Stephen Richard Butter**, Sydney
(AU); **Sun Kyung Sunwoo**, Sydney
(AU); **Pieter Schillebeeckx**, Sydney
(AU); **Yves Amavel Vieira**, Sydney
(AU)

(73) Assignee: **Freedman Electronics Pty Ltd**,
Silverwater (AU)

(**) Term: **15 Years**

(21) Appl. No.: **29/759,284**

(22) Filed: **Nov. 20, 2020**

(30) **Foreign Application Priority Data**

May 22, 2020 (AU) 202012947

(51) **LOC (14) Cl.** **14-01**

(52) **U.S. Cl.**

USPC **D14/228**
